UNITED STATES PATENT OFFICE.

JOHN McVICKER MORRIS, OF MAYFAIR, LONDON, ENGLAND, ASSIGNOR OF TWO-THIRDS
TO TREDEGARS LIMITED, OF MAYFAIR, ENGLAND.

CONSTRUCTION OF GAS-GENERATING APPARATUS.

1,277,457.

Specification of Letters Patent. Patented Sept. 3, 1918.

Application filed January 31, 1917. Serial No. 145,750.

To all whom it may concern:

Be it known that I, JOHN McVICKER MORRIS, a subject of the King of Great Britain, residing at 7 Brook street, Mayfair, in 5 the county of London, England, have invented certain new and useful Improvements in the Construction of Gas-Generating Apparatus, of which the following is a specification.

10 This invention relates to improvements in the construction of gas generating apparatus, more especially intended for the production of acetylene gas. The invention provides a simple and convenient construction 15 of generator of the water displacement type adapted for domestic lighting and other purposes where a compact and easily manipulated generator is required.

According to this invention the gas generator and sludge bucket are combined in 20 one closed gas vessel, placed for generating purposes in an outer water tank and so constructed that on raising the gas vessel or bucket in its closed condition the water in 25 the bucket is lowered below the carbid holder or basket so that further generation of gas ceases. In the construction preferred the bucket is provided with means by which it may be supported in the tank in a raised 30 position with the water clear of the carbid, such means consisting conveniently of a strong hook on one side of the bucket adapted to hook over the edge of the water tank. The carbid basket is preferably made with 35 a rounded bottom and is so constructed that the wires or strips from which it is made do not cross at the center, leaving a clear central space for the sludge to fall through, to avoid danger of such an accumulation at 40 the points of crossing of the wires that the basket becomes choked.

In order that the said invention may be clearly understood and readily carried into effect, we will describe the same more fully 45 with reference to the accompanying drawings, in which:—

Figure 1 is a vertical section of a complete generator constructed according to this invention and Fig. 2 is a plan of the carbid 50 basket.

A is the water tank, shown with an open top. B is the bucket, the lower part of which receives the sludge while the upper part is closed by the cover b so that the 55 bucket serves also as the gas generating ves-

sel. C is the basket mounted on the lower end of the cylinder c and inside the stand c'.

The top of the cylinder c is closed by the hinged cover c² which is raised when the carbid is to be inserted. A handle c³ allows 60 the basket C to be removed from the bucket B, the basket being supported at the upper end of the bucket by the lugs c⁴ which rest on a shoulder in the bucket rim b'. An air cock is fitted in the opening b² of the cover 65 b and in the opening b³ of the cover an outlet cock is fitted leading to the gas burner. The cover b is formed with the channeled rim or lip b⁴ which fits over the upper edge of the rim b'. The cover b is secured firmly 70 on top of the bucket by means of the cross bar D the ends of which engage the lugs b⁵ at each side of the rim b', a screw d passing through the central boss in the bar D and engaging at its lower end with the cover b. 75 A notched disk d' secured by the nut d² on the upper end of the screw d allows the screw to be turned so as to raise or lower the cover b. The bar D is detachable from the lugs b⁵ so that the cover b can be removed and the carbid holder reached. 80

To allow the water in the tank A to enter the bucket B the latter is provided with the channeled plate b⁶ which extends to the bottom of the bucket over the hole b⁷ and 85 is formed with the aperture b⁸ at its upper end so that the water is trapped in the bucket at the level of this aperture. On raising the bucket the water above the aperture is allowed to flow gently out into the 90 tank A until the level is below that of the basket C so that the carbid is no longer supplied with water for generating purposes. Also if pressure is generated in the bucket 95 the gas can drive the water out of the bucket down to the level of the aperture, the water rising again to attack the carbid as soon as the pressure is relieved. The bucket provides a considerable space below the aperture, so that a large quantity of sludge may 100 be collected before it is necessary to empty the bucket. The restricted passage between the interior of the bucket and the tank A, formed by the apertures b⁷ and b⁸ and the channeled plate b⁶, prevents any sudden rush 105 of water into the bucket or splashing out therefrom on lifting out the bucket.

The bucket is lifted by a handle secured to the lugs b⁵, and for convenience in supporting it in the tank A with the carbid 110

above the water level a strong hook E, consisting of a bent iron strip, is fitted to the side of the bucket about the middle so that on raising the bucket it can be hooked on to the edge of the tank and the bucket can then be opened and the carbid basket, already clear of the water, can be lifted out and refilled. The hook plate is formed with an extension e forming a handle to be used when emptying the bucket, the cover and carbid basket having of course already been removed.

The carbid basket C is of special construction and forms a feature of considerable practical importance. In using carbid in lumps of substantial size it has been found that with baskets of ordinary construction, where wires cross not only along the sides but also across the bottom of the basket, the carbid is frequently retained owing to the numerous corners, some of which form acute angles, and the clogging at the bottom where the sludge collects at the points of crossing of the wires. The regularity of action of the generator is thus seriously interfered with and substantial waste of carbid frequently incurred. This irregularity of action is a great disadvantage, especially in cases where the gas is withdrawn at a substantial and as near as possible constant rate.

In the improved basket illustrated the sides are composed entirely of vertical wires or strips without any connecting horizontal wires and the vertical wires c⁵ of one set are continued around to form a rounded or hemispherical bottom while the remaining set c⁶ are merely brought up to the adjacent rounded wires at c⁷ so as to leave the bottom entirely clear of corners which might collect the disintegrating carbid and check the descent of the fresh carbid toward the water. A short length of wire c⁸ is used to connect the bottom wires at each side and well away from the center. Such wires virtually form the continuation of four vertical wires but these are replaced in the construction illustrated by the vertical rods of the stand c', which lie at the corners between the two sets of vertical wires forming the body of the basket. The acute angled corners which would be formed by continuing the cross wires c⁸ into the sides of the basket are thus avoided. The wires c⁵ and c⁶ are secured at their upper ends to the upper ring c⁹ of the stand c'. The wires at the points

of junction are preferably welded together to form a strong construction which is not attacked at the corners by chemical action due to the gas generating materials.

It will be seen that owing to the special formation of the basket, with its rounded bottom and absence of corners near the lowest point, the carbid cannot be checked in its gradual descend by any obstructive action due to corners at which material may collect, since at all points there is a free passage downward and the few corners which are formed are at points well above the bottom so that the carbid or sludge is directed downward and does not tend to collect at such corners.

What I claim and desire to secure by Letters Patent of the United States is:—

1. In a gas generating apparatus of water displacement type, a water tank, a closed gas vessel having a water admission and release aperture situated some distance above the bottom so as to form a sludge bucket, a cover detachably secured to the said vessel at the upper end thereof and having a gas outlet, a carbid basket suspended in the said vessel above the water aperture, and a retaining device on the outside of the vessel adapted to engage the said tank and suspend the vessel when the latter is raised into inoperative position.

2. In a gas generating apparatus of water displacement type, a water tank, a closed gas vessel having a water admission and release passage extending from the bottom to some distance above the latter so as to form a sludge bucket, a cover detachably secured to the said vessel at the upper end thereof and having a gas outlet, a carbid basket suspended in the said vessel above the upper end of said passage and a hook fixed on the outside of the vessel about the middle and adapted to engage on the edge of the tank to suspend the generator in raised position.

3. A carbid basket for use in a gas generator comprising a stand composed of vertical rods and connecting rings, a series of wires secured at their upper ends to the top of the said stand and bent around to form vertical sides and a rounded bottom, and a second series of wires also secured at their upper ends to the stand, completing the vertical sides and secured at their lower ends to the first series without crossing at the bottom of the basket.

JOHN McVICKER MORRIS.
